TOP SAFETY DEVICE FOR RIFLES

Wilfred I. Smith, Chicopee Falls, Mass., assignor
to Savage Arms Corporation, Utica, N. Y., a
corporation of Delaware

Application December 12, 1946, Serial No. 715,800

1 Claim. (Cl. 42—70)

1

This invention relates to safety devices for the firing mechanism of rifles of the general type shown in Patent No. 634,034 of October 3, 1899. In rifles of this kind, a reciprocable bolt for opening and closing the breech and for cocking the piece, is operated by an up and down swinging handle or operating lever pivoted at the underside of the receiver and embodying a trigger guard as a part thereof.

An object of the present invention is to provide a safety device of simple and effective character which may be operated to "on" or "off" position by a thumb piece at the top side of the receiver and within easy reach for manipulation when grasping the hand grip of the stock.

A further object is to provide a safety device which will lock the operating lever against movement whenever the trigger is blocked by an "on" position of said safety. This is for the purpose of preventing an accidental breech opening movement of the operating lever when the safety is "on." Otherwise, it could happen that in carrying the gun loaded and cocked through thick woods that a branch of a tree or other obstruction might catch in the handle of the operating lever to throw the breech open and eject the cartridge.

A further advantage will be appreciated from the fact that in rifles of this character, the cocking of the hammer accompanies a reciprocation of the bolt and the sear action requires that the trigger give way slightly when said hammer is cocked. A safety device which merely blocks the trigger might be inadvertently pushed to "on" position after firing and before the bolt is retracted for recocking. If in such a situation the operating lever were subsequently swung down to retract the bolt, with its accompanying cocking action, it would meet a blocked trigger and a breakage might result therefrom. Insurance against such a contingency is provided in my present safety device by having the same constructed so as to lock the operating lever against movement whenever the trigger is blocked by the "on" position of the safety. This is accomplished by a relatively simple design and arrangement of parts which involves a minimum of alteration in the construction of such standard type of rifle, and can therefore be added to the rifle at low cost.

The full and complete description of my invention will be given in connection with the accompanying drawings in which—

Fig. 1 is a sectional view through the receiver of the rifle showing the firing mechanism with

2

the bolt forward for closing the breech and the safety device in "on" position;

Fig. 2 is a similar view with the bolt in retracted position and the safety device in "off" position;

Fig. 3 is a detail section with the parts as in Fig. 1 and the safety device in "off" position; and

Fig. 4 is a detail fragmentary view of the underside of the receiver looking in the direction of arrows A—A in Fig. 2.

Referring more particularly to the drawing, the gun frame comprises the receiver 1 and gun stock 2 joined together at a hand grip portion indicated at 3. The reciprocable bolt 4 is slidable back and forth in the receiver in the usual manner by the hand operated lever 5. This hand operating lever is pivotally hung to the underside of the receiver by the hinge pin 6, and provides a guard for the trigger as shown and is formed with a handle 7 at the rear thereof. A curved arm 8 integral with handle 7 extends upwardly and forwardly through the receiver and has an operative connection at its forward end 9 with the usual cam slide 10, the latter forming an integral part of the bolt 4.

The firing mechanism is of the usual character for rifles of this type and comprises said bolt with its hammer or striker 11 slidably carried in said bolt and having at its rear end a downwardly projecting hook portion 12 adapted to be engaged by the sear 13 when the piece is cocked as shown in Fig. 1. The sear 13 is pivoted at 14 to the receiver and is provided with the usual sear spring 15. The trigger 16 is pivoted as at 17 in the receiver and has a forwardly extending notched arm 18 operatively engaged through pin 19 with said sear 13. The trigger 16 is also formed with a tail piece 20 extending from the rear side thereof for coaction with the safety device as will be described, and the handle extension 8 is provided with a laterally extending lug 21 also for coaction with said safety device.

The safety device comprises a vertically extending lock lever 22 pivotally mounted within the receiver on pin 23, the latter being carried in a mounting bracket 24 fastened by screw stud 25 to the receiver. The lock lever 22 is vertically positioned in the receiver side by side with the extension 8 of said hand operating lever. As shown in Fig. 4, the bottom of the receiver is formed with a slot at 26 for the hand operating lever extension 8, and a slot at 27 for the lock lever 22 and with a wider slot 28 forwardly thereof through which the trigger 16 extends.

55 The upper end 29 of the lock lever 22 is en-

gaged in a notched portion 30 of a thumb piece 31 which is slidably mounted upon the top side of the gun frame and more particularly at the top forward part of the hand grip portion 3, so that it will be in convenient position for operation by the thumb when one is grasping said hand grip portion. A bent spring 32 and pin 33 are cooperatively associated with this thumb piece 31 so as to yieldingly hold the same in either of its "on" or "off" positions. The lower end of the lock lever 22 is formed into a foot portion 34 with a toe at 35 adapted to coact with tail 20 of the trigger, and a notched heel at 36 adapted to coact with the lug 21 of the hand operating lever.

The operation of the safety device is as follows: When the hand operating lever is home with the hammer cocked, as shown in Fig. 1, the thumb piece 31 may be positioned rearwardly to its "on" position. This will bring the toe 35 in position above the tail 20 of the trigger 16 and block the same from being pulled. At the same time the notched heel 36 of said lever 22 will engage the lug 21 of the lever extension 8 and lock the hand lever 5 from movement. Thus, when the safety is on, both trigger and the hand operating lever are restrained from movement, and when the safety is positioned forward to its "off" position, both of these elements of the gun are free for operation as shown by the position of the parts in Fig. 3.

What I claim is:

The combination of safety mechanism with a rifle of the type comprising a frame including a receiver and gun stock, firing mechanism including a trigger, a reciprocable bolt and a hand lever operatively connected therewith and pivoted to the underside of said receiver for up and down swinging movement in reciprocating said bolt,

said safety mechanism comprising a flat one-piece lock lever, a mounting bracket fastened to the receiver, said lever being pivoted on said bracket centrally of the lever and disposed vertically in said frame with its upper end adjacent the top of the gun stock and its lower end at the underside of the receiver, a finger piece on the top side of said gun stock portion of the frame movable to an "off" and an "on" position and having a depending portion with a forked notch extending within the frame and receiving the upper end of said flat lock lever in said notch, a pin on said depending portion with a bent spring biased against the pin and anchored to the stock to yieldably hold said finger piece and lever in either position of adjustment, the lower end portion of said lock lever being formed with a toe and a notched heel, said trigger having a tail engageable by said toe and said hand lever having a lug on the side surface thereof engageable by said notched heel, said lower end portion of the lock lever lying in a lateral plane at one side of the path of movement of the end lever, said toe and heel simultaneously engaging the trigger and lug on the hand lever to lock both against movement when said lock lever is moved to "on" position.
